UNITED STATES PATENT OFFICE.

CLARENCE S. WOODS, OF DETROIT, MICHIGAN, ASSIGNOR OF ONE-HALF TO ELLSWORTH FORSYTH, OF DETROIT, MICHIGAN.

TOOTHPICK HOLDER AND VENDING MACHINE.

1,122,456.

Specification of Letters Patent.

Patented Dec. 29, 1914.

Application filed February 20, 1914. Serial No. 819,860.

To all whom it may concern:

Be it known that I, CLARENCE S. Woods, a citizen of the United States of America, residing at Detroit, in the county of Wayne 5 and State of Michigan, have invented certain new and useful Improvements in Toothpick Holders and Vending Machines, of which the following is a specification, reference being had therein to the accompanying 10 drawings.

This invention relates to a tooth pick holder and container, and the primary object of my invention is to provide a holder that can be advantageously used in cafés, 15 dining rooms and cars for delivering tooth picks that are inclosed so as to keep them in a sanitary state, from exposure to dust and from being handled.

Another object of this invention is to provide a simple, durable and inexpensive device for effecting single delivery of tooth picks, matches, etc., to individual users, the device being primarily designed as a tooth pick dispensing machine having a novel delivery member that permits of an incased 25 tooth pick being easily removed without any danger of the same being broken.

A further object of this invention is to provide a tooth pick container that can be used in connection with a suitable repository, the retainer being in the form of envelopes connected by weakened tearing portions, which permit of the container being rolled or folded and envelopes singly removed 35 from the end of the outer convolution or fold of the container.

With the above and other objects in view, the invention resides in the novel construction, combination and arrangement of parts 40 to be hereinafter specifically described and then claimed.

Reference will now be had to the drawing, wherein—

Figure 1 is a perspective view of the 45 tooth pick holder; Fig. 2 is a side elevation of the same partly broken away and partly in section; Fig. 3 is a plan of the holder partly broken away and with the lid or cover thereof removed; Fig. 4 is the enlarged perspective view of a tooth pick container 50 partially opened, and Fig. 5 is a cross sectional view of the holder taken on or about the line V—V of Fig. 1.

A holder in accordance with this invention 55 comprises a substantial base or pedestal

1 having the upper end thereof provided with a socket 2 to receive the depending stem 3 of a cylindrical horizontally disposed casing 4. The top of the casing 4 has an opening 5 normally closed by a lid or cover 6 which rests upon the edges of the end walls 7 of said casing and is flush with the side walls of said casing. The inner side of the lid or cover 6 has depending guide lugs 8 engaging the inner sides of the end walls 7 to prevent longitudinal displacement of the lid or cover, and the front edge of said lid or cover has the inner side thereof provided with a lip 9 that facilitates properly positioning the lid or cover upon the casing. 10 The stem 3 of the casing serves as a swivel therefor whereby the casing can be swung to a desired position to permit of access being had to the front side of the casing, which is provided with a flat radially disposed delivery case or member 10. The delivery case or member 10 provides a lateral delivery slot or opening 11 in communication with the interior of the casing 4. The case or member 10 has an outer wall 12, which has 15 one end thereof cut away, as at 13, at an opening 14 in the bottom wall 15 of the case or member 10. The opening in the bottom wall 15 is at one side of the case or member and said bottom wall has another opening 16 20 at the opposite side of the case or member. A top wall 17 of the case or member has the outer end thereof provided with an oblong opening 18 vertically alining with the opening 14 of the bottom wall and extending 25 from said opening to a point in proximity to the inner end of the opening 16, as best shown in Figs. 1 and 5, these openings being essential as will hereinafter appear. The top and bottom walls 17 and 15 of the 30 case or member 10 are further cut away to provide finger recesses in communication with the openings 14 and 18, said finger recesses being designated 19 and coöperating with the openings 14 and 18 in exposing a 35 portion of a tooth pick container whereby the same can be easily removed from the case or member 10.

Loosely arranged within the casing 4 is a roll or folded strip of containers 20, each 40 connected by a weakened tearing portion 21. The weakened tearing portions 21 are 45 equally spaced and are formed by providing the longitudinal edges of the strip of containers with parallel slits that extend in- 50

wardly to the ends of parallel rolls of perforations, the slits being designated 22 and the perforations 23, as best illustrated in Fig. 3 of the drawing. The container may 5 be made up in various ways, for instance, by folding a strip of paper longitudinally of its length, placing tooth picks between the folds, an adhesive between the tooth picks, pressing the folds together until they 10 ad- here, and then slitting and perforating the strip, thus connecting the containers in a manner that insures sufficient flexibility for the strip to be drawn through the case or member 10 and the containers singly torn 15 and removed therefrom. The end of the container strip can be easily inserted in the case or member 10 whereby the end of the strip will be exposed at the outer end of the case or member, and the width of the open- 20 ings 14 and 18 correspond to the width of a single container, whereby the container will lie between the openings 14 and 18 and extend over the opening 16 in the bottom plate 15 of the case or member 10. The weakened 25 tearing portions of the strip of containers registers with the inner walls of the openings 14, 16 and 18, and the outer container can be easily gripped and torn from the strip and removed. The inner edge of the 30 opening 18 and the inner edge of the opening 16 serve as cutting edges when a container is torn or removed from the strip, said openings providing clearance for the container whereby a tilting movement of the 35 container severs the same and permits of its removal. The finger recesses 19 permit of the end of the strip being gripped and drawn forward whereby the next container can be torn and removed.

40 A container or envelop maintains the tooth pick in a sanitary condition and the design of the same is such that it can be readily used for advertisement purposes, also for dispensing other articles. The shape of 45 the holder casing is really immaterial but the construction of the outer end of the case or member 10 is essential in order that only one container can be removed at a time without any danger of the same being unduly 50 torn or the contents thereof broken or injured.

While in the drawing there is illustrated a preferred embodiment of my invention, it is to be understood that the structural elements are susceptible to such changes, as in 55

the size, proportion and manner of assem- blage, as fall within the scope of the appended claims.

What I claim is:

1. A holder comprising a casing adapted 60 to contain a strip of rigid containers, and a member in communication with said casing and having the outer end thereof provided with openings whereby a container can be tilted to project an end through each open- 65 ing and permit of the removal of said container from said member.

2. A holder comprising a swiveled casing adapted to contain a strip of rigid contain- 70 ers, a member forming part of said casing and having the end thereof cut away to ex- pose a container whereby it can be tilted to project the ends of a container above and below the member and permit of its removal 75 therefrom.

3. A holder comprising a casing adapted 80 to contain a strip of rigid containers, and a member in communication with said casing and adapted to receive the end of the strip of containers, said member having the outer 85 end thereof provided with openings to ex- pose the end of the strip of containers whereby the ends of a container can be pro- jected above and below the member to per- mit of its removal therefrom.

4. A holder of the type described, com- 90 prising a casing adapted to contain a strip of rigid containers, a lateral member carried thereby and provided with an opening in communication with said casing, said mem- 95 ber having the top and bottom walls thereof cut away at its outer end to expose an end of the strip at the end of said member and permit of the ends of the container being projected above and below said member and removed therefrom.

5. A tooth pick holder comprising a mem- 100 ber adapted to contain tooth picks, said member having the top and bottom walls thereof provided with openings whereby a toothpick can be tilted to project ends there- 105 of through the openings and permit of the removal of said toothpicks from said mem- ber.

In testimony whereof I affix my signature 105 in presence of two witnesses.

CLARENCE S. WOODS.
